MODEL SPEED BOAT

John W. McRoskey, Los Angeles, Calif.

Application October 22, 1954, Serial No. 32,768

Term of patent 14 years

(Cl. D71—1)

FIG. 1.

FIG. 2.

FIG. 3.

FIG. 5.

FIG. 4.

To all whom it may concern:

Be it known that I, John W. McRoskey, a citizen of the United States, residing at Los Angeles, in the county of Los Angeles and State of California, have invented a new, original, and ornamental Design for a Model Speed Boat, of which the following is a specification, reference being had to the accompanying drawings, forming part thereof.

Fig. 1 is a top view of a model speed boat showing my new design;

Fig. 2 is a side view;

Fig. 3 is a bottom view;

Fig. 4 is a view from the forward end; and

Fig. 5 is a view from the rear end.

I claim:

The ornamental design for a model speed boat, as shown.
